UNITED STATES PATENT OFFICE.

JAMES AUSTIN PAGE, OF PHILADELPHIA, PENNSYLVANIA, ASSIGNOR TO
THE ABRAM COX STOVE COMPANY, OF SAME PLACE.

DESIGN FOR AN ORNAMENTAL FIRE-PLACE LINING.

SPECIFICATION forming part of Design No. 16,131, dated June 16, 1885.

Application filed May 15, 1885. Term of patent 3½ years.

To all whom it may concern:

Be it known that I, JAMES AUSTIN PAGE, a citizen of the United States, residing at Philadelphia, in the county of Philadelphia and State of Pennsylvania, have invented and produced a new and original Design for an Ornamental Fire-Place Lining, of which the following is a specification, reference being had to the accompanying photograph, forming a part thereof.

The photograph (marked B) gives a clear perspective view, and shows completely the full character of my new design.

It consists of one small rosette, with a square pyramidal center repeated eighty times in horizontal lines, eight in a row, upon the back, and the same rosette repeated fifty

times in horizontal lines, five in a row, upon each of the side jambs. These one hundred and eighty rosettes, so arranged upon the respective plain surfaces as a base, have also in squares at all the places between them small globular ornaments, as clearly shown in the photograph.

I claim—

The design for an ornamental fire-place lining, consisting of small rosettes having a square pyramidal center and small globular ornaments interspersed in all the open squares around them, as shown in the photograph.

J. AUSTIN PAGE.
